UNITED STATES PATENT OFFICE.

ROWLAND H. BOONE, OF SPRINGFIELD, OHIO, ASSIGNOR TO EDEN WASHER CORPORATION, OF NEW YORK, N. Y., A CORPORATION OF DELAWARE.

CYLINDER FOR WASHING MACHINES.

Application filed July 19, 1924. Serial No. 727,025.

This invention relates to a cylinder for washing machines, and it is an object of this invention to simplify the construction and assembly of such cylinder for reducing 5 the cost of manufacture.

The invention comprises the novel structure and combinations hereinafter described and more particularly pointed out and defined in the appended claim.

10 In the accompanying drawings which illustrate a preferred embodiment of this invention and in which similar reference numerals refer to similar features in the different views,

15 Figure 1 is an elevational view of my improved washing cylinder.

Figure 2 is an enlarged sectional view upon the line 2—2 of Figure 1.

20 Figure 3 is an enlarged fragmentary sectional view through the cylinder at one of the baffle plates.

Figure 4 is an enlarged fragmentary sectional view through one of the cylinder heads taken in a longitudinal direction.

25 Figure 5 is an enlarged broken sectional view taken upon the line 5—5 of Figure 3.

Figure 6 is an enlarged broken longitudinal sectional view of the cylinder taken adjacent the sliding door thereof.

30 Figure 7 is a broken fragmentary elevational view of a cylinder having a hinged door.

Figure 8 is an enlarged fragmentary sectional view of the cylinder at the hinge of the door.

35 Figure 9 is an enlarged fragmentary sectional view of a cylinder head and the hinged doors.

Referring now to the drawing, the number

40 1 represents a perforated cylindrical member or sheet of metal, the ends of which extend into under-cut grooves 2 in the peripheral heads 3 of end heads 4 that close the cylinder. These end heads 4 are in the

45 form of solid metal plates or the like, a series of recesses or sockets being formed circumferentially of the interior of these end heads adjacent the outer periphery. Each recess or socket is formed by a pair of parallel

50 radially extending lugs 5 (Figure 3) and a medial lug 6. The sockets in the respective heads are in alinement, and baffle plates 7

which in the present instance are shown as made of wood have their ends supported in opposite recesses. These baffle plates are 55 provided with longitudinally extending grooves 8 through which adjustable bolts or rods 9 extend and which are provided with heads 10 engaging the outer surface of said heads. In the present instance, each 60 rod consists of two sections, the end of one section being threaded in the end of the other section as shown in Figure 5. Consequently, when a wrench or key is applied to the heads, the sections may be relatively rotated for extending or contracting the rod. When such rotation contracts the rod, it is 65 evident that the heads 4 will be drawn tightly against the ends of the perforated cylindrical member 1.

70 The clothes to be washed are adapted to be put in this cylindrical member and for this reason, the same must be provided with a suitable opening and door therefor. In the embodiment shown in Figure 1, a sliding arcuate door 11 which is suitably perforated is confined for sliding movement in the grooves of the heads 4, said grooves being suitably enlarged for such a purpose. By sliding this door 11 in the proper direction an opening for the insertion of clothes will be uncovered. Instead of using a sliding door, an arcuate perforated door 12 may be hinged to the cylinder adjacent the opening through which the clothes are inserted. 85

I am aware that numerous details of construction may be varied through a wide range without departing from the principles of this invention, and I therefore do not purpose limiting the patent granted otherwise than necessitated by the prior art.

90 I claim as my invention:

In a device of the class described, a perforated cylindrical shell, a pair of heads having grooves for receiving the ends of said shell, baffles extending between said heads, means on said heads for supporting said baffles, and adjustable rods extending through said baffles and connecting said heads, each of said rods comprising a pair 95 of telescopic, threaded members.

100 In testimony whereof I have hereunto subscribed my name.

ROWLAND H. BOONE,
